YARN FEED DISABLING APPARATUS FOR HOSIERY KNITTING MACHINES

Kerwin R. Boyer and Ronald Shaw, High Point, N.C., assignors to The Singer Company, New York, N.Y., a corporation of New Jersey

Filed May 31, 1966, Ser. No. 554,172

2 Claims. (Cl. 66—138)

ABSTRACT OF THE DISCLOSURE

Access to the interior of the needle cylinder of a hosiery machine is obtainable by lifting the dial of such machine. To prevent the dial from striking yarn feed fingers as such dial is swung upward, "all" yarn feed fingers of such machine are dropped to below the ordinary level of the dial, thereby freeing such dial for its upward swing.

This invention relates in general to hosiery knitting machines, and in particular to an improved technique for allowing ready access to the interior of the needle cylinder of a hosiery knitting machine through which knitted stockings are adapted to pass.

To gain access to the interior of a hosiery knitting machine it is ordinarily necessary that the dial assembly, including the dial and its cap, of the machine be swung out of and away from its overlying relationship with respect to the top end of the needle cylinder. To swing the dial assembly away from the needle cylinder requires that the yarn feed fingers—which when not actuated to their respective yarn feeding positions usually overhang the dial assembly along a collision course therewith—be repositioned out of the arcuate swing of the dial assembly so as not to be broken or damaged thereby. Present practice for positioning the yarn feed fingers is to engage such fingers by suitable means, and to swing them "upwardly" and arcuately away from the needle cylinder. This necessitates not only a large yarn feed finger swing, but also a swing that is generally directed into and toward the complexly cluttered mechanisms already atop the machine.

To overcome the disadvantages of the prior art, the present invention suggests, not the arcuate lifting of yarn feed fingers for needle cylinder access, but rather the simultaneous arcuate lowering of all of the yarn feed fingers to generally their respective yarn feeding positions, whereby such feed fingers are all positioned out of the arcuate upward swing of the dial assembly, and this in an extremely simple way.

A principal object of the invention is to provide improved apparatus for use with hosiery knitting machines.

Another object of the invention is to provide improved apparatus for use in positioning the yarn feed fingers of a hosiery knitting machine for access to the needle cylinder of the machine.

Another object of the invention is to provide yarn controller apparatus for hosiery knitting machines that permits of easy access to the needle cylinder of the machine without need for upwardly swinging the yarn feed fingers of the controller.

The invention will be described with reference to the figures wherein:

FIG. 1 is a side elevational view of a presently preferred form of the invention,

FIG. 2 is a view, partially cutaway, showing details of construction of the apparatus of FIG. 1,

FIG. 3 is a plan view of the apparatus of FIG. 1,

FIG. 4 is a side sectional view, partially cutaway, taken from FIG. 3, and

2

FIG. 5 is a perspective view useful in teaching the concepts of the invention.

Referring to the figure, a hosiery knitting machine has a needle cylinder 10 having the usual complement of needles, jacks, etc., which needle cylinder is supported for rotation about its axis by means not shown. Drivable with the needle cylinder 10 is a dial assembly 12 having a gear drive 14 that is adapted to be driven by the needle cylinder drive. The dial assembly includes the usual dial 16, in which locates transfer bits for the making of stocking welts, and a dial cap 18 for a cam or cams actuating the transfer bits. The dial assembly 12 is arcuately positionable upwardly away from the needle cylinder 10 along an arc 20 to gain access to the needle cylinder interior.

Surrounding the needle cylinder 10 is a ring type member 22, against the top face 24 of which respective yarn feed fingers 26 (a, b, c etc.) of feed stations A and B, respectively, are adapted to rest when in yarn feeding engagement. The yarn feed stations A, B are essentially identical and, generally hereafter, though only the feed station A is referred to, the description is relevant also to feed station B. A yarn feed controller 30 cooperates to select which of the respective yarns Y is to be fed to the needles 32 of the needle cylinder 10. The yarn feed fingers 26 are pivotally supported, between a pair of braces 33, on a shaft 34, and are so spring biased by respective springs 36 that the feed fingers 26 are urged toward the ring type member 22. Designed to keep the yarn fingers 26 up and out of yarn feeding engagement with the ring type member 22 are respective finger control levers 38, which levers are selectively disabled as will be described later to allow the feed fingers 26 to drop selectively into operation.

The finger control levers 38 are rotatably supported on a shaft 40 in a generally U-shaped carriage 42. The shaft 40 extends, at both of its ends from the carriage 42 and resides in elongated slots 44 in a support post 46. Steady-ing the carriage 42 for up-down translational positioning are bosses 48, also residing in elongated slots 50 in the support post 46. A comb 52 having slots 54, serves to keep the front ends of the control levers 38 in fixed spaced apart relationship; and a comb 56 similarly operates on the back ends of the levers 38.

A control drum 58 is rotatably supported on a sprag 60 between brackets 62 that are formed as part of the support post 46. The control drum 58 is provided with peripherally located jacks 64 which serve to assert counterclockwise forces (looking at FIG. 1) on the levers 38 by bearing against their respective bosses 66, thereby exerting counterclockwise torques on the respective feed fingers 26 about their supporting shaft 34, and against the tensions of the respective springs 36. Absence of a butt on a jack 64 (when the carriage 42 is in the position shown in FIG. 1) releases a particular lever 38, which in turn releases a feed finger 26 to reside against the face 24 of the ring type member 22 for yarn feeding purposes.

An arm member 68 is rotatably supported on the controller sprag 60, and rotatably supports a pawl 70 that is biased by a spring 72 into engagement with a ratchet 74 fixedly secured to the drum 58. The pawl arm member 68 so supports a bar 76 that upward reciprocation of a pawl drive 78 causes a second pawl 80 to drop from disengagement into engagement with a second ratchet 82, which ratchet 82 is the same as, but counter oriented with respect to, the ratchet 74 and is also secured to the drum 58. The pawl 80 is rotatably supported by a bracket 84, and is spring biased by a spring 86 to ride against the bar 76.

A shaft 90, notched sufficiently wide as at 92 to accommodate the control lever carriage 42, is rotatable in the support post 46 by means of a lever 94. With the lever

94 locked in place (see FIG. 1) by means of a carriage lock 96, the carriage rests atop the full diameter of the shaft 90, whereby the levers 38 and their bosses 66 are engaged for actuation by the jacks 64 of the feed control drum 58; with the lever 94 rotated as shown by FIG. 2, the control lever carriage 42 drops into the shaft notch 92, whereby the lever bosses 66 are all disengaged from the drum jacks 64, thus permitting the feed fingers 26 to drop into place against the ring type member 22 of the machine.

As can be readily appreciated, the prior need for cumbersomely upwardly swinging the feed fingers 26 along a wide arc (which incidentally is of even a more critical nature for the feed station B) to get them out of the way of the dial assembly 12—when there is need to raise the dial assembly—is obviated in the present instance by the simple expedient of disabling the feed control drum 58 from the feed finger control levers 38. That is to say, by dropping the lever carriage 42 into the shaft notch 92 (see FIG. 5) by means of the lever 94, the feed fingers 38 are all permitted to swing slightly accurately downwardly, by just enough to allow the dial assembly 12 to swing free and clear along its arc 20.

While the invention has been described in its preferred form, it is to be understood that the words which have been used are words of description rather than of limitation and that changes within the purview of the appended claims may be made without departing from the true scope and spirit of the invention.

Having thus set forth the nature of the invention, what is claimed herein is:

1. In a hosiery machine of the type having a slotted needle cylinder, needles contained within the slots of said needle cylinder, a plurality of yarn feed fingers for supplying yarn to said needles, a dial assembly adapted for cooperation with the needles, capable of being selectively lifted to a point above said needle cylinder so that access to the interior of said needle cylinder may be gained, apparatus for use in so positioning the yarn feed fingers of said hosiery knitting machine that said fingers avoid contact with the dial assembly of said machine when said assembly is raised above the needle cylinder of said machine comprising first means for use in selectively moving the fingers into and out of yarn feeding position

with respect to the needles of said machine, second means for disabling said first means and for positioning all said feed fingers substantially into their respective feeding positions with respect to the needle cylinder of said machine, whereby said fingers cannot be contacted by said dial assembly, and means for operating said second means, said yarn feed fingers being biased into their respective feeding positions with respect to the needle cylinder of the machine, said first means including respective levers for said fingers for normally suspending said fingers above said needle cylinder in their respective non-feeding positions against their respective biases, and control means for engaging said levers and for selectively operating on said levers to release the respective feed fingers to their respective feeding positions, said second means being means for disengaging all said levers from said control means, and including a carriage, means for pivotally supporting said levers in said carriage, and means for so positioning said carriage that said levers may contact, or not, said control means.

2. The apparatus of claim 1 wherein said means for positioning said carriage includes bracket means, a shaft rotatably supported within said bracket means, said shaft having a notch at least as wide as a given side of said carriage, means for so supporting said carriage within said bracket means for translational movement therein in continual contiguous relationship with said shaft that said carriage may, or may not, ride in said notch depending on the angular orientation of said shaft, thereby defining two positions for said levers with respect to said control means.
